UNITED STATES PATENT OFFICE

WARD N. GERE, OF SYRACUSE, NEW YORK, ASSIGNOR, BY MESNE ASSIGNMENTS, TO ECLIPSE TEXTILE DEVICES INCORPORATED, OF ELMIRA HEIGHTS, NEW YORK, A CORPORATION OF NEW YORK

APPARATUS FOR TREATING YARN IN HOLLOW MASS FORMATION

Application filed May 18, 1926. Serial No. 109,930.

This invention relates to apparatus for treating yarn in hollow mass formation. A particular object of the invention is to provide an improved, efficient and economical apparatus for carrying out the method of spotting yarn in mass formation by means of centrifugal force which is described and claimed in my co-pending application, filed November 3, 1925, Serial No. 66,533, on which 10 U. S. Patent No. 1,724,015, was issued on August 13, 1929.

Apparatus embodying my present invention differs from that shown in my aforesaid application in many particulars, including 15 an arrangement by which the hollow cone or other mass of yarn is supported in an upright position and rotated about a vertical axis.

The main object in rotating the yarn cone about its vertical axis is to obtain a higher 20 rate of speed of rotation with less vibration, less wear upon the journal bearings, greater rapidity and uniformity of coloring and a greater output of the resultant production than would be possible by revolving the same 25 cone about a horizontal axis or by any other method thus far known in this art.

These yarn cones are usually wound upon hollow conical cones in such manner that the 30 yarn strands of adjacent layers cross each other diagonally thereby producing a highly porous mass of yarn of uniform radial thickness throughout its length and of substantially the same taper as that of the core.

Owing to this high degree of porosity of 35 the mass of yarn it is found that the coloring fluid introduced into the interior of the cone may be forced outwardly through the porous mass by centrifugal force due to the high speed rotation of the cone without the use of 40 alcohol or equivalent penetrating agent commonly used in coloring fluids to assist their penetration into the yarn and this elimination of alcohol from the coloring liquid greatly simplifies and reduces the cost of the spot-coloring process and apparatus and also assures a more uniform coloring of the restricted zones to which the coloring fluid is applied.

Another object is to provide means for 50 restraining the periphery of the yarn cone

from outward expansion by centrifugal force of the high speed rotation of the cone.

Another object is to provide means for maintaining a balanced co-axial relation between the revolving cone holder and the core supporting mandrel so as to assure uniform 55 distribution of the coloring fluid to the restricted zones of the yarn cone by reducing to a minimum the vibration incidental to the high speed rotation of those parts.

Other objects and uses relating to specific 60 parts of the process and apparatus will be brought out in the following description.

In the drawings:—

Figure 1 is a top plan of my improved apparatus for carrying out the improved 65 process.

Figure 2 is an enlarged vertical sectional view taken on line 2—2, Figure 1, except that the motor is shown in elevation.

Figure 3 is a detail sectional vertical view 70 of a portion of the same apparatus showing the means for lubricating the upper journal bearing for the cone holder.

As illustrated, this apparatus comprises 75 an upright cylindrical frame —1— having its lower end adapted to be clamped by bolts —2— to a bench or other available support and its upper end provided with a removable cap —3— which is secured in place by what is commonly known as a bayonet lock so that it may be easily and quickly removed and replaced by a slight angular movement thereof relatively to the main body of the frame.

The cylindrical frame —1— is provided intermediate its ends with a horizontal portion —4— dividing the interior thereof into lower and upper compartments —5— and —6— and provided with a vertically elongated cylindrical guide opening —7— co-axial with the axis of the cylinder —1—.

A cylindrical bearing sleeve —8— is tightly fitted or otherwise secured in the guide opening —7— to extend beyond the lower 95 and upper ends thereof for receiving and supporting lower and upper ball bearings —9— and —10— and outer and inner retaining rings —9'— and —9"— and —10'— and —10"— therefor, the outer ball retaining 100

rings —9'— and —10'— being tightly fitted in annular recesses in corresponding ends of the sleeve —8—.

A hollow tapered cone holder or cage 5 —11— is mounted in an upright position in the upper compartment —6— to rotate about its vertical axis co-axial with the axis of the cylinder —1— and sleeve —8— with its bottom portion overhanging the upper end of 10 said sleeve and provided with a central depending hub —12— extending into the upper end of the sleeve and through the adjacent inner ring —10''— in which it is tightly fitted or otherwise secured to cause the ring to rotate therewith within the outer ring —10'— through the medium of the interposed ball-bearings —10—, said rings being provided with annular grooves or ball races for receiving the balls —10— and thereby constituting 20 radial as well as end thrust bearings to firmly hold the cage —11— against lateral or axial movement relatively to the sleeve —8— while permitting free rotation of said cage.

An upright shaft —13— is secured at its 25 upper end in a central opening in the hub —12— co-axial with the cage —11— and has its lower end extended through and beyond the lower end of the sleeve —8— for receiving and supporting a pulley —14— and an adjusting nut —15— engaging the lower threaded end of the shaft and adjacent end of the pulley.

This pulley —14— is provided with a reduced forwardly extending hub —14'— 35 tightly fitted within or otherwise secured to the inner ring —11— to cause the latter to rotate therewith, said hub extending above the ring —9''— and threaded externally for receiving a lock nut —16— for additionally locking the ring —9''— to the hub of the pulley.

The ball-retaining rings —9'— and —9''— are provided with annular grooves or ball races for receiving the balls —9— which serve 45 as end thrust and radial bearings to hold the pulley and lower end of the shaft —13— and incidentally the cage —11— against lateral or endwise movement relatively to the bearing sleeve —8—.

50 The pulley —14— is preferably splined by means of a key —17— to the lower end of the shaft —13— to permit axial adjustment of the pulley and cage against their respective bearings to take up wear, these adjustments being effected by means of the nut —15—.

In other words, a slight tightening of the nut —15— will cause a corresponding upward movement of the pulley —14— and its bearing ring —9''— and will also effect a 60 corresponding downward movement of the cage —11— and its bearing ring —10''— thereby tightening both ball bearings in one operation.

The cage —11— is flared upwardly or tapered downwardly to correspond to the taper

of the yarn cone as —A— which it is adapted to receive and retain against radial expansion when the cage with the cone therein is being rotated at a high rate of speed for coloring purposes, it being understood that the interior diameter of the cage is made to correspond approximately to the diameters of standard sizes or weights of cones —A—.

These yarn cones are adapted to be wound upon a hollow tapered core as —a— of cardboard or equivalent material so that the mass of yarn wound thereon will be of uniform radial thickness, the yarn of adjacent layers being arranged to cross each other diagonally thereby rendering the mass of wound 70 75 80 yarn highly porous.

The peripheral wall of the cage —11— is foraminous in that it is provided with a plurality of apertures —a'— throughout the major portion of its area for the passage of 85 the coloring matter therethrough and into the compartment —6— in a manner hereinafter described.

The cover plate —3— is provided with a central internally threaded aperture —18— 90 for receiving an externally threaded hollow bushing 19 co-axial with the axis of the cage —11— and preferably extending some distance beyond the lower and upper faces of the cover plate —3— to form an adjustable 95 support for the hub as —20— of a rotary cone-supporting mandrel —21—.

The hub —20— is preferably made separate from the mandrel —21— and has its lower end threaded and screwed into a 100 threaded socket in the upper end of the mandrel to permit the use of mandrels of different tapers or sizes as may be required for differently tapered cones.

The mandrel —21— and its hub —20— are 105 also provided with central lengthwise openings for receiving an upright section —22— of the feed pipe for the coloring liquid, said section —22— being connected by a flexible pipe —23— to a reservoir —24— for the coloring fluid which is controlled by a valve 110 —25—. The central lengthwise openings in the mandrel —21— and its hub —20— are of slightly greater diameter than the pipe section —22— to permit free rotation of the 115 mandrel relatively to and without friction with the pipe section.

The object of the flexible connection —23— is to permit the cover —3— and parts carried thereby including the mandrel —21— and yarn cone —A— to be removed and replaced relatively to the cage —11— and ease —1— 120 without disconnecting the feed pipe from the mandrel or disturbing any of the other parts of the apparatus.

The central lengthwise opening in the mandrel —21— extends the major portion of the length thereof but is closed at its lower end and has its intermediate portions provided with annular enlargements or distributing 125 130

chambers —26— and —26'— in axially spaced relation between the lower and upper ends of the yarn cone —A— and its core —a— for receiving the coloring fluid. The mandrel —21— is also provided with lower and upper sets of radial passages —27— and —27'— leading from the chambers —26— and —26'— respectively through the walls of the mandrel to communicate with similar sets of passages —28— and —28'— in the conical core —a— and thereby to permit the passage of the coloring fluid through the registering portions of the yarn cone —A— by centrifugal force as the cone is rotated.

15 The mandrel —21— is also provided with relatively shallow peripheral grooves —29— and —29'— registering with the lower and upper sets of perforations —27— and —27'— and perforations —28— and —28'— to allow 20 a free distribution of the coloring fluid to the registering portions of the yarn.

The lower chamber —26— is of preferably smaller capacity than the chamber —26'— while the upper half as —30— of the passage 25 connecting said chambers is preferably flared upwardly or gradually enlarged from a level substantially midway between the chambers so as to facilitate the even distribution of the coloring liquid to both chambers when dis- 30 charged into the lower chamber.

The lower end of the color supply pipe —22— terminates substantially midway between the chambers —26— and —26'— or at about the beginning of the upward flare of the 35 connecting passage between said chambers leaving sufficient clearance around the lower end of the pipe for the passage of the fluid from the lower chamber to the upper chamber.

40 It is to be understood that when the mandrel and cone supported thereby are revolved at a high rate of speed while the coloring matter is introduced through the pipe —22— into the interior of the mandrel this coloring matter is thrown by centrifugal force against the walls of the central passage and tends to rise from the lower chamber —26— upwardly along said walls and by flaring the upper end of the connecting passage between the chambers facilitates the even distribution of the 45 coloring fluid from the lower chamber —26— to the upper chamber —26'— and thence outwardly by centrifugal force from said chambers through the radial passages leading 50 therefrom into and through the registering portions of the yarn for producing the desired spotting of the yarn when it is unwound from the cone for knitting into fabrics as, for example, undergarments and the like.

55 The hub —20— is journaled in the bushing —19— by anti-friction ball-bearings —31— which are held in vertically spaced relation by an interposed spacing sleeve —32— surrounding the intervening portion of the hub.

60 The ball-bearings of each set are held in

operative position by suitable retainers, each consisting of an inner ring —33— and an outer ring —34—.

The portion of the hub —20— which extends through the inner retainer ring —33— and spacing sleeve —32— is reduced in diameter to form an annular shoulder at the inner end of the lower retainer while the upper end of the hub extends beyond the upper retainer and is threaded externally for receiving an 75 adjusting nut —35—.

The bushing —19— extends upwardly above the adjusting nut —35— and is provided with a central internally threaded opening of sufficiently large diameter to permit the ball-retainers and sleeve —32— to pass therethrough, said opening being normally closed by a screw plug —36— which is held in its adjusted position by a set screw —37—.

The inner rings of the lower ball-retainer are interposed between the lower end of the sleeve —32— and annular shoulder on the hub —20— while the inner rings of the upper ball-retainer are interposed between the upper end of the sleeve —32— and nut —35— which serves to firmly clamp the inner rings of both retainers and sleeve —32— to said hub.

The outer rings of the lower ball-retainer are seated on an inturned annular flange on the lower end of the bushing —19— while the outer rings of the upper ball-retainer are seated against the lower end of the screw plug —36— which may be adjusted to take-up wear of both of the ball-retainers simultaneously, said screw plug being provided with apertures in its upper face for receiving a spanner wrench, not shown.

The bushing —19— may also be adjusted vertically by rotation in the cap section —3— for raising and lowering the mandrel —21— and parts carried thereby but more particularly for properly setting the yarn cone against the peripheral walls of the cage —11— to assure sufficient friction between those parts for transmitting rotary motion from the cage to the yarn cone and mandrel.

The means for rotating the cage —11— preferably consists of an electric motor —M— mounted in an upright position upon a suitable supporting frame —B— and having the lower end of its armature shaft provided with a pulley —C— which is connected by a belt —c— to the pulley —14— on the lower end of the cage shaft —13—.

The frame —B— is hinged at —b— to suitable brackets —b'— on the one side of the cylindrical casing —1— to swing about a vertical axis and has its opposite side adjustable toward and from the casing to tighten the belt, said adjusting means consisting of a screw stud —d— on the frame —1— and opposed adjusting nuts —e— engaging said stud and the inner and outer faces of the 130

adjacent portion of the frame —B— as shown in Figure 1.

Suitable means is provided for lubricating the bearings for the shaft —13— consisting in this instance of a radial oil passage —f— in the partition —4— leading from the upper bearing —10— to the outer side of the casing and having its outer end provided with an oil pocket —f'— into which the lubricant may be introduced, the periphery of the hub —12— of the cage —11— being provided with a spiral groove —g— for distributing the oil to the bearing —10— and also allowing some of the oil to drop into the lower bearing —9— through the interior of the sleeve —8—.

The cap —3— is provided with suitable handles —3'— by which it may be unlocked and removed from the upper end of the casing —1— to permit the removal and replacement of the mandrel —21— and parts carried thereby from the interior of the cage —11—.

The chamber —6— is provided at its lower end with a drainage pipe —6'— to allow any excess coloring liquid which may be expelled through and from the yarn cone —A— to be collected and re-used if desired.

A brake member —38— is movable radially at will in an aperture in the upper portion of one side of the casing —1— into engagement with the periphery of the upper end of the cage —11— for quickly retarding or stopping the rotation thereof, after the coloring operation, said brake member being normally held out of engagement with the cage 35 by a retracting spring —38'—, Figure 2.

While the apparatus which has been described is of special value in carrying out my method of spotting yarn by centrifugal force, it is apparent that the apparatus may also be 40 used for other purposes.

Operation

The cover —3— carrying the mandrel —21— and feed pipe —22— is first unlocked 45 and removed from the case —1— after which the yarn cone as —A— with its conical core —a— therein is placed by hand upon the mandrel after which the cover with the mandrel and cone thereon is replaced and locked upon 50 the top of the case with the periphery of the yarn cone frictionally engaged with the peripheral walls of the cage —11—.

The motor is then started to rotate the cage together with the yarn cone and mandrel therein at a high rate of speed of say, 55 3400 revolutions per minute during which the coloring liquid is allowed to flow in limited quantities through the pipe —22— and into the interior of the mandrel where it is first 60 discharged into the lower chamber —26—.

Portions of this coloring liquid will rise by 65 centrifugal force to the upper chamber —26'— and the coloring liquid will then be expelled by centrifugal force through the apertures —27— and —27'— and —28— and

—28'— through the registering portions of the porous yarn cone —A— and thence outwardly through the apertures —a'— in the cage into the interior of the casing —1— thereby coloring the restricted zones of the 70 yarn which, when unwound, will be colored in spots throughout its length.

The surplus coloring liquid which may lodge in the chamber —6— may be drawn off through the drain pipe —6'— and re-used 75 if desired. Owing to the high speed of rotation of the cage —11— and yarn cone therein it is evident that the coloring liquid will quickly pass in radial zones through the yarn thereby affording an expeditious and efficient 80 method of coloring the yarn in spots.

Under this process the yarn may be rapidly and efficiently colored without the use of alcohol in the coloring liquid thereby eliminating one of the major items of expense in 85 coloring processes of this character.

The mandrel —21— may be adjusted through the medium of the screw bushing —19— to expand and frictionally bind the core —a— against the interior of the yarn 90 cone —A— to not only assure transmission of rotary motion from the cone to the mandrel and frictional engagement of the periphery of the yarn cone with the peripheral walls of the cage but also serves to prevent upward 95 displacement of the portion of the yarn cone adjacent the mandrel due to the tendency of the yarn to separate from the core by centrifugal force in which case the upward flare of the mandrel resists the tendency to upward 100 movement of the contiguous portions of the yarn and assure the retention of the original form of the yarn cone during the coloring process.

It will also be evident that the upward adjustment of the screw bushing —19— may be used to release the mandrel from the core and thereby permit the free removal of the core with the colored yarn thereon following said 105 coloring operation.

Just before the cover —3— is raised to permit the removal of the mandrel and colored cone the screw —19— is unscrewed sufficiently to release the mandrel from engagement with the core —a— by upward displacement and if the core should tend to lift with the mandrel by adhesion thereto it will engage an overlying annular flange —8— on the under side of the cover to effect a stripping of the core from the mandrel and thus permit the mandrel to be withdrawn by the upward displacement of the cover leaving the core in the yarn cone —A—.

After the cover and mandrel have been removed by upward displacement the yarn 125 cone —A— may be withdrawn through the upper end of the cage —11— by means of a ring —r— engaging the lower end of the yarn cone at the outside of the core —a—, said ring being provided with diametrically oppo- 130

site, relatively thin and narrow arms extending upwardly along the inside of the cage between the peripheral walls thereof and the periphery of the cone and having their upper ends provided with handles —*h*— extending through the open upper end of the cylinder —*1*— for withdrawing the colored cone —*A*— upwardly.

What I claim is:—

1. In an apparatus for treating yarn wound in hollow cone formation, opposed co-axially mounted cone supporting elements rotatable about a vertical axis, and provided with means for frictionally engaging the outer and inner peripheries of the yarn cone, the frictional engagement of said yarn cone serving to transmit rotary motion from one element to the other, and means for rotating one of said elements with the yarn cone between them.

2. In an apparatus for spot coloring yarn wound in hollow cone formation, opposed co-axially mounted cone supporting elements rotatable about a vertical axis, and provided with means for frictionally engaging the outer and inner peripheries of the yarn cone, the frictional engagement of said yarn cone serving to transmit rotary motion from one element to the other, means for applying a coloring fluid to a limited portion of the interior area of the yarn cone, and means for rotating one of said elements.

3. In an apparatus for spot coloring yarn wound in hollow cone formation, co-axially mounted supporting elements for frictionally engaging the outer and inner peripheries of the yarn cone, means for rotating one of said elements, and means for applying a coloring liquid to a limited area of the interior of the cone during its rotation.

4. In apparatus for treating yarn wound in hollow cone formation, opposed internal and external supporting elements independently mounted for rotation about a common axis and frictionally engaging the outer and inner surfaces of the yarn cone, the frictional engagement of said yarn cone serving to transmit rotary motion from one element to the other, and means for rotating one of said elements with the yarn cone between them.

5. In apparatus for treating yarn wound in hollow cone formation, opposed internal and external supporting elements independently mounted for rotation about a common axis and frictionally engaging the outer and inner surfaces of the yarn cone, the frictional engagement of said yarn cone serving to transmit rotary motion from one element to the other, means for rotating one of said elements with the yarn cone between them, and means for applying a coloring fluid to the inner surface of the yarn cone during the rotation.

6. In apparatus for treating yarn wound

in hollow cone formation, opposed coaxial supporting elements rotatable about a common axis, means for causing an approaching movement of said elements along their common axis to force them into frictional engagement with the inner and outer surfaces of the yarn cone, and means for rotating one of said elements.

7. In apparatus for treating yarn wound in hollow cone formation, opposed coaxial supporting elements rotatable about a common axis, means for causing an approaching movement of said elements along their common axis to force them into frictional engagement with the inner and outer surfaces of the yarn cone, means for rotating one of said elements, and means for applying a coloring fluid to the inner surface of the yarn cone during such rotation.

8. In apparatus for treating yarn wound in hollow cone formation, opposed cone supporting elements, independent bearings for said elements supporting them in coaxial relation, said elements frictionally engaging the outer and inner surfaces of the yarn cone so that the yarn cone may serve to transmit rotary motion from one element to the other, and means for rotating one of said elements with the yarn cone between them.

9. In apparatus for treating yarn wound in hollow cone formation, opposed cone supporting elements, independent bearings for said elements supporting them for rotation about a common axis, means for causing a relative approaching movement of said bearings along said common axis to bring the elements into frictional engagement with the inner and outer surfaces of the yarn cone, and means for rotating one of said elements.

10. In apparatus for treating yarn wound in hollow cone formation, the combination of a casing, a detachable cover for said casing, a conical cage rotatably mounted in the casing and having its larger end open and adapted to engage the outer surface of a yarn cone, a conical mandrel rotatably mounted in the cover and coaxial with the cage when the cover is applied to the casing and adapted to engage the inner surface of a yarn cone, and means for rotating one of said rotatably mounted elements.

11. In apparatus for dyeing yarn wound in hollow cone formation, the combination of a casing, a detachable cover for the casing, a conical cage rotatably mounted in the casing and having its larger end open, a hollow shaft rotatably mounted in the cover and coaxial with said cage when the cover is applied to the casing, a conical mandrel secured to the inner end of said hollow shaft and having peripheral openings and a passage connecting said openings with the bore of the hollow shaft, means for rotating one of said rotatably mounted members after the cover has been applied to the casing, and

means for introducing dye through the hollow shaft into the mandrel.

12. In apparatus for treating yarn wound in hollow cone formation, opposed co-axial supporting elements engaging respectively the inner and outer surfaces of the cone, means for rotating one of said elements, and thrust bearings preventing a separating movement of said element during such rotation.

13. In apparatus for treating yarn wound in hollow cone formation, the combination with means for rapidly rotating the yarn cone, of means for preventing the yarn on the inner surface of the cone from moving towards the larger end of the cone, and for preventing the yarn on the outer surface of the cone from moving towards the smaller end of the cone under the effect of centrifugal force.

14. In apparatus for treating yarn wound in hollow cone formation, the combination with means for rapidly rotating the yarn cone, of means for positively preventing the yarn on the inner and outer surfaces of the cone from shifting longitudinally under the effect of centrifugal force.

15. In apparatus for spot-dyeing yarn wound in hollow mass formation, a rotatable mandrel extending into the hollow of the yarn mass, containing an axial passage for the introduction of coloring liquid and spaced radial passages, and having peripheral grooves connecting the outer ends of said radial passages to distribute the coloring liquid over the surface of the mandrel between said radial passages.

16. In apparatus for spot-dyeing yarn wound in hollow mass formation, the combination of a rotatable mandrel entering the hollow of the yarn mass and containing an axial passage and spaced sets of radial passages, and means for introducing a coloring liquid into said axial passage at a point between said radial passages.

17. In apparatus for spot-dyeing yarn wound in hollow mass formation, the combination of a rotatable mandrel entering the hollow of the mass and containing an axial passage and spaced sets of radial passages, and a color supply pipe extending into the axial passage of the mandrel and terminating between said sets of radial passages.

18. In apparatus for spot-dyeing yarn wound in hollow mass formation, the combination of a rotatable mandrel entering the hollow of the mass and containing axially spaced distribution chambers and an axial passage connecting said chambers and radial passages extending outward from each chamber, and means for introducing coloring liquid into said axial passage between said chambers.

19. In apparatus for spot-dyeing yarn wound in hollow mass formation, the com-

bination of a rotatable mandrel entering the hollow of the mass and containing axially spaced distribution chambers and an axial passage connecting said chambers and radial passages extending outward from each chamber, and a color supply pipe entering the axial passage in the mandrel and terminating in said passage between said chambers.

20. In apparatus for spot-coloring yarn wound in hollow mass formation, the combination of a rotatable mandrel entering the hollow of the mass and containing spaced distribution chambers and radial passages extending outward from said chambers and an axial passage connecting said chambers and flaring outwardly towards each chamber from a constricted central portion, and means for introducing a coloring liquid into said passage at its constricted central portion so that the liquid is distributed to the chambers along the flaring portions of the passage by centrifugal force.

21. In apparatus for spot-dyeing yarn wound in hollow mass formation, a mandrel rotatable about a vertical axis, entering the hollow of the mass from its upper end and containing spaced upper and lower distribution chambers and radial passages extending outwardly from said chambers and an axial passage connecting said chambers and flaring outwardly towards its upper end, and means for introducing coloring liquid into the lower chamber, so that the dye may be distributed from the lower to the upper chamber along said flaring passage by centrifugal force.

In witness whereof I have hereunto set my hand this 10th day of May 1926.

WARD N. GERE.
